C. G. HAWLEY

LOCOMOTIVE BOILER

Filed May 13, 1922

C. G. Hawley
Inventor.

UNITED STATES PATENT OFFICE.

CHARLES GILBERT HAWLEY, OF CHICAGO, ILLINOIS, ASSIGNOR TO LOCOMOTIVE FIRE-BOX COMPANY, OF CHICAGO, ILLINOIS, A CORPORATION OF DELAWARE.

LOCOMOTIVE BOILER.

Application filed May 13, 1922. Serial No. 560,660.

My invention relates to locomotive boilers and the object thereof is to increase the capacity and efficiency of such boilers. To that end I very considerably increase the 5 firebox heating surface and provide means which cause or set up a positive fore-and-aft circulation of the water in the boiler. My invention comprises, in combination with the locomotive firebox, a hollow water 10 table extending transversely across the firebox and in communication with the side water legs of the boiler, plus a substantially triangular vertical hollow wall which rises from the top of the water table portion and 15 extends through the crown sheet of the firebox, presenting therein an outlet opening equalling, and indeed, much exceeding in size the combined intake areas of the water table portion. These and other features of 20 my invention will be readily understood on reference to the accompanying drawing, in which Fig. 1 is a vertical longitudinal section of a locomotive boiler firebox embodying my invention. Fig. 2 is a transverse section thereof substantially on the line 2—2 25 of Fig. 1. Fig. 3 is a horizontal section substantially on the line 3—3 of Fig. 1 and Fig. 4 is an enlarged sectional detail substantially on line 4 of Fig. 1.

As here indicated, my invention comprises 30 a water-circulating-and-steaming attachment of a kind which may be applied to any locomotive boiler firebox already in existence or which may be built into a new firebox. 35 Primarily it is intended for fireboxes of the medium and wide sizes which are of such form as to permit the attachment in its completed form to be hoisted into the firebox through the bottom of the same, when the 40 grate is removed. In the drawings 2 represents the flue sheet of the firebox. 3 is the crown sheet. 4 is the back sheet and 5, 5, are the side sheets of the firebox. The 45 flues are marked 6. The dotted line 7 represents the normal grate surface. It will be understood that the firebox is secured to and supported from the shell 8 of the boiler by means of the usual longitudinal and transverse rows of stay-bolts. The long 50 radial or crown bolts are marked 10; and the short water leg stay-bolts are marked 11.

My novel attachment comprises the rearwardly and upwardly inclined hollow water table portion A and the vertical water wall 55 portion A'. The table portion is substan-

tially rectangular and is stay-bolted throughout, as is well shown in the drawing. The vertical portion A' is of substantially triangular form, beginning at the lower front end of the portion A and rising thence to the crown sheet. The bottom 12 of the rear part of the portion A' is inclined upwardly and rearwardly in the form of an extension or continuation of the inclined water table portion. By this form I avoid 60 the possibility of trapping mud or sediment in either part of the attachment. The portion A is stay-bolted throughout as indicated. The water table contains a water space 13 of about one-half the width of the 65 water space 14 in the part A'; and the length of the water table is preferably about one-half the length of the open top of the water wall A'. Thus I provide both an ample 70 intake area for the device and an ample outlet area. The ends of the water table are joined to the edges of opening 16 in the side sheets 5, 5, preferably by means of elongated diaphragm (corrugated) attachment plates 17, as well shown in Fig. 4. For the effective 75 strengthening of these connections I dispose therein two of the rows of stay-bolts 11'. The top of the attachment is applied to the crown sheet in a manner substantially 80 identical with that shown in Fig. 4, though 85 it may quite well be directly attached to the edges of the complementary opening in the crown sheet.

All flanges and curves of the device are 90 well rounded to avoid abrupt angles, as best indicated at points 18 in Figs. 2 and 4.

It should be noted that the lower front end or edge of the hollow water table is 95 widely spaced from the flue sheet 2, my purpose being to avoid localizing expansion and contraction strains in the neighborhood of the flue sheet. The space between the two parts is normally closed by a transverse row of firebrick 19, as well shown in Figs. 1 and 3.

The water table portion of this device forms an admirable fire arch in the firebox and the extensive vertical water wall not only provides an ample circulation of water 105 through the water table, but also serves to further sub-divide the flame body in the firebox with obvious advantages.

In operation the device causes a vigorous fore-and-aft circulation of the boiler water with marked improvement in the efficiency 110

of all of the heating surfaces of the boiler.

Having thus described my invention, I claim as new and desire to secure by Letters Patent:

- 5 1. In combination with a locomotive firebox having a crown sheet and side sheets, a water steaming and circulating element arranged in the firebox and embodying therein, a vertically disposed flat tubular water leg arranged longitudinally of the firebox and having an elongated discharge mouth opening through the crown sheet and a rearwardly and upwardly inclined bottom wall, said element also including a flat tubular water table extending transversely of the firebox with an inlet at each end which opens through the side sheets of the firebox, said water table being inclined in the angle of the bottom wall of the water leg and 10 communicating therewith at the bottom end thereof.
- 15 2. A locomotive boiler firebox having a flue sheet in combination with an upwardly and rearwardly inclined stay-bolted water table portion extending transversely across said box and at the ends in communication with the side water legs of the firebox, a
- 20
- 25

substantially triangular stay-bolted vertical water wall extending between said water table and the crown sheet of the firebox and 20 providing an ample circulatory outlet for said water table, both said table portion and said vertical portion being spaced rearwardly from the flue sheet, and a refractory brick arch extending between the forward 25 edge of the water table and the flue sheet.

3. A water steaming and circulating element for locomotive boilers and adapted to be located in the firebox thereof and comprising a vertically disposed flat tubular, 40 triangularly shaped water leg having an elongated top opening and an inclined bottom wall, and a flat tubular water table arranged transversely of the water leg and in the inclined plane of the bottom wall of 45 said water leg and with which it communicates, said water table having inlet openings at its ends, the planes of said water leg and table being disposed at a right angle 50 to each other.

In testimony whereof, I have hereunto set my hand this 6th day of May, 1922.

CHARLES GILBERT HAWLEY.
